UNITED STATES PATENT OFFICE.

JAKOB GRUSE, OF CITY ISLAND, NEW YORK.

INVALID-CHAIR.

SPECIFICATION forming part of Letters Patent No. 308,606, dated December 2, 1884.

Application filed October 15, 1883. (No model.)

To all whom it may concern:

Be it known that I, JAKOB GRUSE, a citizen of the United States, residing at City Island, in the county of Westchester and State of New York, have invented certain new and useful Improvements in Invalid-Chairs, of which the following is a specification, reference being had therein to the accompanying drawings.

This invention relates to improvements in a combined chair or lounge for invalid and surgical operations, with bath-tub and commode attachments, and has for its objects to provide an easy chair for bed-room uses, an infant's bath-tub, as a bath-tub for the use of patients with piles, as a tub for the convenience of patient in administering a vaginal douche, as a close stool or night chair for sickness. These objects are attained by the mechanism illustrated in the accompanying drawings, forming a part of this specification, in which—

Figure 1 is an elevation showing the entire device as an easy chair or lounge. Fig. 2 is a transverse section on the line $x-x$ of Fig. 1. Fig. 3 is the seat of the chair taken from the under side. Fig. 4 is a plan view of the chair, with some of the parts removed, showing the seat for the close stool. Fig. 5 is the mechanism for raising and lowering and holding the adjustable back at different angles to the seat removed and showing the construction in detail.

The letter A indicates the removable seat of the easy chair or lounge, which is provided with a rim, A', which fits over the top of the case for the bath-tub C.

B is the removable seat for the close stool.

C is the bath-tub, which may be removed from the case D, if desired. The case D is provided with a rubber edge, J, for the ease of the patient.

E are the detachable legs of the chair, four in number, which are secured to the case D by screws E', whereby they may be removed from the case when it is desired to do so.

F is the adjustable back, which is secured 45 to the case D by the hinges G G' and the screw attachment H, by means of which the back F may be set and held at different angles by turning the wheel H', which is adapted to turn the screw H in either direction and 50 cause the back F to rise or fall at different angles by the action of the nut H", which is secured thereto. The hinge G' is composed of two lugs secured to the case D, and a rock-shaft, G", having bearings therein. The rock-shaft G" is provided with a central opening, in which the lower end of the screw H is fitted and secured in such manner that it is permitted to turn freely therein.

I are hooks on the bottom of the case D, and 60 are intended to hold the seat for the close stool B when not in use. These hooks are three in number, and are arranged with respect to each other as clearly shown in Figs. 1 and 2 of the drawings, so as to hold the seat 65 B by the edges when not in use, the said seat being pushed in under the body A from the rear.

The seat A is intended to be upholstered, as shown in the drawings, and also the stool- 70 seat B.

Having described my invention, what I desire to secure by Letters Patent and to claim is—

The combination, in an invalid chair or 75 couch, of the hollow body or case D, provided with hooks I at the bottom, and with supporting-legs E, and the removable seats A and B, the latter being adapted to be held at the edges by the hooks when not in use, substantially as specified.

In testimony whereof I affix my signature in presence of two witnesses.

JAKOB GRUSE.
